UNITED STATES PATENT OFFICE

102,511

DESIGN FOR A BREAD CABINET

George W. Stallings, Jackson, and George W. Walker, Pleasant Ridge, Mich., assignors, by direct and mesne assignments, to A. Kreamer, Incorporated, New York, N. Y., a corporation of New York

Application May 22, 1936, Serial No. 62,787

Term of patent 14 years

To all whom it may concern:

Be it known that we, George W. Stallings and George W. Walker, citizens of the United States, the former residing in the city of Jackson, Jackson county, Michigan, and the latter in Pleasant Ridge, Oakland County, Michigan, have invented a new, original, and ornamental Design for Bread Cabinets, of which the following is a specification, reference being had to the accompanying drawing, forming part thereof.

We claim:

The ornamental design for a bread cabinet, as shown.

GEORGE W. STALLINGS.
GEORGE W. WALKER.
